UNITED STATES PATENT OFFICE.

CHARLES J. MAYER, OF PHILADELPHIA, PENNSYLVANIA.

DESIGN FOR A RAIL-BOND.

SPECIFICATION forming part of Design No. 32,020, dated December 19, 1899.

Application filed November 18, 1899. Serial No. 737,527. Term of patent 14 years.

To all whom it may concern:

Be it known that I, CHARLES J. MAYER, a citizen of the United States, residing at the city of Philadelphia, in the county of Philadelphia and State of Pennsylvania, have invented and produced a new, useful, and original Design for a Rail-Bond, of which the following is a specification, reference being had to the accompanying drawings, forming part ¹⁰ hereof, in which—

Figure 1 is a top or plan view of the rail-bond of the design of my invention, and Fig. 2 is a side view of the same.

The leading feature of my design consists ¹⁵ of the particular shape or configuration and arrangement of the rail-bond.

Referring to the drawings, *a* and *a'* represent the end recessed brackets, each provided with projecting plugs *a²* and *a³*.

²⁰ *b* and *b'* represent outer and inner bands, each composed of a series of closely-nested narrow metal strips, both of which are offset at *b²* and *b³*, the respective bands contouring

with each other about the middle and beyond on both sides of the middle of the bond, as illustrated in Fig. 1 of the drawings, and respectively joined to the end brackets, so as to provide the irregular openings *c* and *c'* between the outer and inner bands and within the inner band the irregular openings *d*, *d'*, and *d²*, ²⁵ ³⁰ the openings *d* and *d²* being of a different form or shape from the form or shape of the opening *d'*.

Having thus described my invention, what I claim as new, and desire to secure by Letters ³⁵ Patent, is—

The design for a rail-bond, substantially as herein shown and described.

In testimony whereof I have hereunto set my signature in the presence of two subscribing witnesses. ⁴⁰

CHARLES J. MAYER.
